[57] CLAIM

The ornamental design for a combined address and notebook, as shown and described.

DESCRIPTION

FIG. 1 is a perspective view of a combined address book and notebook showing my new design;
FIG. 2 is an enlarged scale bottom end elevational view thereof;

FIG. 3 is a plan view of FIG. 1 in the open configuration showing the interior; and
FIG. 4 is a plan view of the exterior of FIG. 3.
